(57) **CLAIM**

The ornamental design for a cocktail shaker, as shown and described.

DESCRIPTION

FIG. 1 is a front, left and top perspective view of a cocktail shaker, showing my design.

FIG. 2 is a rear, left and bottom perspective view thereof.

FIG. 3 is an enlarged front elevation view thereof.

FIG. 4 is an enlarged rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled **9** in FIG. 1; and,

FIG. 10 is a partial enlarged view of an area labeled **10** in FIG. 2.

The broken lines shown in the drawings are included for the purpose of illustrating portions of the cocktail shaker that form no part of the claimed design. In addition, the dot-dash broken lines in FIGS. 1, 2 and 9-10 depict the boundaries of the enlargements that form no part of the claimed design.
